P. G. KAISER

BOILER CIRCULATOR

Filed Jan. 5, 1925

UNITED STATES PATENT OFFICE.

PAUL G. KAISER, OF CHICAGO, ILLINOIS.

BOILER CIRCULATOR.

Application filed January 5, 1925. Serial No. 473.

My invention relates to an improvement in fire tube boilers, whereby a more efficient circulation can be effected. The chief object of my invention is the prevention of the so-called end circulation or longitudinal movement of the water in circulating over the fire tubes.

In Patent No. 880,080 previously granted to me February 25, 1908, I disclosed the use of spaced baffle plates between groups of fire tubes which would shield a vertical region from the heat of the tubes and thus provide a relatively cool vertical passageway for the downward flow of water. A further object 15 of my present invention is to check any tendency toward end circulation in boilers equipped with the plates of my prior patent, and to check the longitudinal flow especially in the regions between the spaced plates. 20 Another object is to retard the tendency of the water above the uppermost tubes to flow longitudinally.

A still further object of my invention is to provide some means of further retarding 25 end circulation in boilers where, because of their expense or for other reasons, it is not feasible to supply additional circulating plates. I contemplate also the use of means for checking the longitudinal flow of the 30 water in its upward movement as well as in its downward movement.

Still another object of my invention is the elimination of vibration or rattling of 35 the spaced circulating plates shown in my aforesaid patent, which would tend to wear away the walls of the fire tubes.

These and additional objects and advantages of my invention are set forth in the 40 following description of a specific embodiment thereof, which is illustrated in the accompanying drawings, wherein

Figure 1 is a longitudinal vertical section through a boiler provided with my circulators on the line 1—1 of Fig. 2;

Figure 2 is a transverse section through 45 the boiler; and

Fig. 3 is a transverse fragmentary section taken on the line 3—3 of Fig. 2.

The boiler 10 is supported above the furnace chamber 11 with the ends of the fire tubes 12 opening into the fire chamber 13, while their other ends open into the smoke box 14. The fire tubes 12, which are arranged in vertical tiers rather than being

vertically staggered, are divided by vertical 55 spaces 15 into one central and two outer groups. In each space 15 is a pair of circulating plates 16 disposed in contact with the respective adjacent tiers of fire tubes and suspended by angle iron bracket strips 17 60 riveted to the plates and curved outwardly at the upper ends to embrace the upper tubes of the adjacent tiers, as indicated at 18. The circulating plates terminate six inches or so short of the ends of the boiler and 65 are positioned against longitudinal displacement in transit by stop bars 19 riveted on their ends and extending into abutment with the boiler ends.

The use of the circulating plates as thus far described, adds greatly to the capacity of the boiler because it confines a major portion of the downward flow of water to the relatively cool spaces between the plates which shield the spaces from the heat of the fire tubes. The downward flow of water between these plates is not resisted by the upward force of the hot water, as would be the case if no place for plates or spaces were provided and the water was left to find its way downwardly between the closely spaced heated tubes. As is well known to boiler engineers, the tendency of the water is to flow upwardly at the ends of the fire tubes and 70 downwardly intermediate their ends in 75 something of a cross flow, so that the circuit resembles a laterally disposed figure 8.

The spaced plates, however, do not eliminate this circuitous end-to-end flow of the 80 water which impedes the speedy and direct circulation of the water essential to securing a maximum capacity and efficiency for the boiler. In carrying out my present invention, I provide a plurality of transversely 85 disposed baffle strips 20 which in appearance are not unlike large T-squares, for their upper ends are provided with baffle heads 21 adapted to overlie the upper fire tubes of the adjacent tiers and support the baffle strips 20. In installing these baffle strips, 90 especially in boilers already in use which are provided with the spaced baffle plates, I prefer to take the strips into the boiler 95 through the manhole 22 and pass them upwardly between the plates in a plane parallel thereto and then, after the baffle head 21 is above the tops of the tubes, twist the strip 20 to its transverse position and, if 100 105

necessary, pound the strip down so that the baffle head rests on the upper tubes.

The strips 20 are preferably slit a considerable distance inwardly from their lower ends and the bifurcated strips normally spread apart, so that after the strips are finally positioned between the plates they tend to urge the plates apart under strong tension and into firm engagement with the adjacent tier of tubes, whereby any vibration against the tube is precluded and there is no danger of the continued knocking of the plates against the tubes in time wearing holes through the walls of the tubes.

The water which flows downwardly between the spaced circulating plates 16 is confined to a substantially vertical movement, and since most of the downward flow of water is between the plates, the end circulation as to the downward flow at least, is prevented. While the transverse baffle strips 20 do not themselves directly preclude end or longitudinal circulation of the up-flowing water, they do prevent it indirectly by confining the downward portion of the water circuit to vertical paths. The ordinary tendency of the up-flowing water alone is to travel vertically, and it is the unequal counter-pressures of the downwardly flowing water which start end circulation.

In most boilers the normal boiler level is several inches above the tops of the tubes, and as this region is unobstructed in the ordinary boiler, it is the region where the colder water will most easily travel longitudinally. Water is forced upwardly over the regions of the boiler having the greatest heat, and the water naturally will flow longitudinally above the tubes toward areas over the cooler regions of the tubes where it can flow downwardly. It is thus apparent that a great deal of the end circulation of the water originates in the region above the tubes, and if the end circulation can be checked at its source, it will be unable to develop to a serious extent. It is with a view to checking this end circulation at its source that I provide the previously mentioned baffle heads 21 which, if desired, may be longer than I have shown to form a more complete transverse barrier above the tubes. I use the baffle heads at the tops only of the strips 21, thereby permitting convenient access to the lower part of the boiler.

In the drawings I have shown the central group of fire tubes divided by a narrow space 23 much less in width than the spaces 15, but greater than the distance between the other tiers of tubes. In this space I place narrower baffle strips 24 provided with baffle heads 25 at their upper ends and suspended thereby. The lower ends of these strips are preferably provided with cross members 26 engaging the lower tubes of the adjacent tiers to position the strips. In this central

space 23 the distance between the tiers of tubes is not very great and there are no circulating plates to shield it from the heat of the adjacent fire tubes. The temperature of the water in the space 23 is therefore almost as high as that between any of the tiers of tubes. There is not sufficiently lower temperature to cause the water to travel downwardly through the space, but instead the water will travel upwardly as it does between the other tubes, but at a somewhat faster rate of flow. This flow, however, is confined by the strips 24 to vertical paths.

Although I have shown this particular furnace construction as an embodiment of my invention, it is to be understood that many changes may be made without departing from the scope or spirit of my invention.

What I claim is:

1. The combination with a boiler, of horizontal fire tubes therein arranged to provide a pair of adjacent groups with a vertical space therebetween, a pair of spaced vertical circulating plates disposed in the space for providing for the downward flow of water therebetween, and transverse vertical strips at longitudinal intervals between the plates of the pair for precluding longitudinal circulation between said plates.

2. The combination with a boiler having horizontal fire tubes arranged in vertical tiers with enlarged spaces between certain of the tiers, of a circulator for the boiler comprising a pair of spaced vertical circulating plates disposed along the sides of the respective tiers of tubes adjacent each enlarged space, and transverse circulating strips extending across the height of the plates and disposed therebetween at spaced longitudinal intervals for confining water passing between the plates to vertical paths to the exclusion of longitudinal flow.

3. The combination of a boiler, a multiplicity of horizontal fire tubes arranged in a pair of adjacent groups leaving a vertical space therebetween, a pair of spaced circulating plates disposed within the space and in contact with the fire tubes adjacent the respective sides of the space, means for suspending the plates at their upper edges, and transverse baffle strips extending substantially the height of the plates and disposed therebetween, the lower ends of the strips embodying means for spreading the lower edges of the plates apart to hold them under tension against the fire tubes, whereby pounding of the plates against the fire tubes is precluded.

4. The combination with a boiler having a multiplicity of fire tubes therethrough arranged to form a vertical space extending from the upper fire tubes to the lower fire tubes and provided with spaced vertical circulating plates in said space suspended from their upper ends and in contact with the

adjacent fire tubes, of a plurality of transverse strips extending transversely between the plates at spaced intervals for precluding longitudinal flow of water between the plates, the strips being slit a distance inwardly from their lower ends and the bifurcations of the strips thus formed being sprung apart for urging the plates into tensional contact with the adjacent fire tubes 10 for preventing pounding of the plates thereagainst.

5. The combination of a boiler, a number of horizontal fire tubes arranged in a pair of adjacent groups with a vertical space 15 therebetween, the uppermost tubes being a spaced distance below the normal water level of the boiler, spaced vertically disposed circulating plates in said space, a plurality of transverse circulating strips between the 20 plates whereby the downwardly flowing water is confined to vertical paths, the strips extending to the uppermost tubes and thereabove being provided with transverse baffle heads for checking longitudinal circulation 25 of the water above the tubes.

6. The combination with a boiler having a multiplicity of horizontal fire tubes, the uppermost of which are a spaced distance below the normal water level of the boiler, 30 of a plurality of transverse baffles between the uppermost tubes and the water level spaced throughout substantially the length of the boiler for directly checking the longitudinal flow of water.

35. 7. In a boiler, a shell, a multiplicity of horizontal fire tubes extending therethrough and arranged in groups leaving a vertical space therebetween, the uppermost tubes being a spaced distance below the normal 40 water level, a vertically disposed circulating plate extending through said space transversely thereof, and a transverse baffle head secured to the upper end of the strip and extending over the adjacent fire tubes at the 45 upper end of the strip for checking the longitudinal flow of water above the tubes and for vertically positioning the strip.

8. A boiler comprising a shell, a multiplicity of longitudinal fire tubes therein arranged in groups with a vertical space between adjacent groups defined by fire tubes of said groups for affording a relatively free 50 passage for water heated by said defining fire tubes, and vertical baffle strips disposed 55 at intervals along the space and extending

transversely thereof for precluding longitudinal movement of the upwardly flowing water in the space.

9. A boiler comprising a shell, a multiplicity of longitudinal fire tubes therein arranged with a vertical space between adjacent groups defined by fire tubes of said groups for affording a relatively free passage for water heated by said defining fire tubes, vertical baffle strips disposed at intervals along the space and extending transversely thereof for precluding longitudinal movement of the upwardly flowing water in the space, the uppermost of the adjacent tubes being a spaced distance below the normal water level of the boiler, and baffle heads at the upper ends of the strips extending transversely across said last mentioned tubes for checking the longitudinal flow of the water after it has flowed upwardly above the 75 level of the tubes.

10. The combination with a boiler of a multiplicity of longitudinal fire tubes arranged in groups with vertical spaces therebetween, a pair of spaced vertical baffle plates 80 in one of said spaces for shielding the space therebetween from the heat of the adjacent fire tubes whereby the space is left comparatively cool to permit the downward flow of water between the plates, vertical baffle strips 85 disposed transversely between the plates for confining the water flowing downwardly therebetween to vertical paths, a second vertical space between adjacent groups defined by fire tubes of said groups for affording a 90 relatively free passage for water heated by said defining fire tubes, and vertical baffle strips disposed at longitudinal intervals along the second space and extending transversely across the second space for confining the upwardly flowing water therein to vertical paths.

11. The combination with a boiler having a multiplicity of horizontal fire tubes therein arranged to provide a pair of adjacent 100 groups with a vertical space therebetween, of a pair of spaced vertical plates disposed in the space providing a passage for the down flow of water, and means for checking longitudinal flow of water in said passage comprising a vertical strip disposed transversely 105 between said plates at a mid point thereof.

In witness whereof, I hereunto subscribe my name this 31 day of December, 1924.

PAUL G. KAISER.
